US00D631729S

(12) **United States Design Patent**
Bucci

(10) **Patent No.:** **US D631,729 S**
(b4) **Date of Patent:** **** Feb. 1, 2011**

(54) **DEVICE FOR SUPPORTING AN OBJECT**(76) Inventor: **Michael Bucci**, 5770 Oak Mill Ct., Glen Allen, VA (US) 23059(**) Term: **14 Years**(21) Appl. No.: **29/355,157**(22) Filed: **Feb. 3, 2010****Related U.S. Application Data**

(60) Continuation of application No. 29/352,511, filed on Dec. 22, 2009, now Pat. No. Des. 613,582, which is a continuation of application No. 29/343,675, filed on Sep. 17, 2009, now Pat. No. Des. 609,077, which is a division of application No. 29/334,086, filed on Mar. 20, 2009, now Pat. No. Des. 603,245, which is a continuation-in-part of application No. 29/326,489, filed on Oct. 20, 2008, now Pat. No. Des. 602,341, which is a continuation-in-part of application No. 29/283,426, filed on Aug. 14, 2007, now Pat. No. Des. 581,251, and a continuation-in-part of application No. 29/295,012, filed on Sep. 20, 2007, now Pat. No. Des. 581,254.

Primary Examiner—Cynthia M Chin*(74) Attorney, Agent, or Firm*—Brian J. Teague(57) **CLAIM**

I claim the ornamental design for a device for supporting an object, as shown and described.

DESCRIPTION

FIG. 1 is a perspective view of one embodiment of a device for supporting an object showing the new design;

FIG. 2 is a front elevational view thereof;

FIG. 3 is a rear elevational view thereof;

FIG. 4 is a top view thereof;

FIG. 5 is a bottom view thereof;

FIG. 6 is a perspective view of an alternative embodiment of a device for supporting an object;

FIG. 7 is a front elevational view thereof;

FIG. 8 is a right side elevational view thereof;

FIG. 9 is a rear elevational view thereof;

FIG. 10 is a left side elevational view thereof;

FIG. 11 is a top view thereof; and,

FIG. 12 is a bottom view thereof.
